UNITED STATES PATENT OFFICE

CLARENCE E. REED, OF WICHITA, KANSAS

WELL-CASING HOLDER AND ELEVATOR

Application filed June 15, 1927. Serial No. 198,989.

The invention relates to an improvement in well casing or tubing holder and elevator.

An object of this invention is to provide an improved mechanism to be used for efficiently holding pipe or tubing for lowering into or removing from a well bore.

Another object of this invention is to provide an improved type of pipe holder embodying a novel type of mechanism which eliminates lateral movement of the jaws, thereby preventing the jaws contacting tangentially with the pipe. Conventional casing holders have their supporting links set with the axial line of the link tangent to the circle of the pipe, and such mechanisms are built up of so many different pieces requiring freedom for movement that under the loads imposed on the mechanism the combined required clearance of the movable parts pulls the area of the slips out of their theoretical contact with the pipe so that the slips contact on a point or line only, instead of their entire area. This invention places the supporting mechanism in a radial line directly opposed to the line of thrust of the load on the mechanism and the slips being made in segments loosely held are free to adjust their contacting area fully to the irregular exterior of the pipe.

Another object of this invention is to provide removable wearing surfaces at the ends of the links which may be replaced as the occasion may require.

The usual practice is to construct holders of a cast soft steel, which metal compresses under the very heavy, concentrated loads imposed on the mechanism. Such compression, small in itself, in the aggregate of all the parts, is sufficient to distort the assembly of the tangentially arranged conventional supporting mechanism, as relates to contact of the slips on the pipe.

The removable wearing surface of this invention permits the parts to be made of metals especially adapted for the purpose, and heat treated to develop their full properties, further adding not only to the strength of the assembly but also to the smoothness and ease of operation.

Other objects and advantages of the invention will be apparent from the descrip-

tion and will be more particularly pointed out in the claims. Similar reference characters designate corresponding parts throughout the several views in the drawings illustrating the preferred form of my invention, 55 in which

Figure 1 is a view partly in transverse section through my improved holder showing the link and jaw mechanism, and also showing in dotted outline means for receiving the lower ends of the bails, not shown, used with elevator.

Fig. 2 is a plan view of the invention, partly in section, and with the means for attachment of elevator bails omitted.

Fig. 3 is a plan view of the base member only of a spider with detachable segment.

Fig. 4 is a perspective view of the smaller segment of the base member.

Fig. 5 is a view of the face of the larger 70 segment of the base, showing the recess 1^b, into which the projection 1^c is fitted.

Fig. 6 is a view of the face of the larger segment of base, showing the surface adapted 75 to make a butt joint with the small segment 75 of base.

As is well known and understood by those skilled in the art to which this invention relates, the holder may be employed either as a casing support on a platform at the mouth 80 of the well, or as an elevator, in which event bails not shown are attached in the conventional manner to the base at eyes 9 indicated in dotted outline in Fig. 1. It is customary to use both an elevator and a casing support 85 upon a platform in the operation of lowering a casing into the well or removing it therefrom. One serious difficulty with elevators in use is the tendency to wedge so tightly under load that the slips must be 90 jarred loose with a heavy sledge. My invention eliminates this trouble.

In the drawings 1 is the base of the holder; 2 is a link; 3 is a jaw; 4 are segmental slips which are held by brackets 5 secured to the jaws by screws 11. The ends 4' of the segmental slips are turned to a cylindrical shape and rest in holes 5' in the bracket of larger diameter than the cylindrical end of the slip. The slips are therefore free to turn about the 100

axis of the ends 4' so that the teeth 4" thereon may adjust themselves to the surface of the pipe. In the drawings, three segments are shown in each jaw, and there being four jaws, the assembly, as shown, comprises twelve segmental slips. Conventional casing holding mechanism commonly employ two segments; occasionally where the spider is a one piece forging or casting three segments are used. 5 In either case the area of the slip does not contact with the surface of the pipe to the extent or as effectively as the arrangement of my invention.

The spiders in general use employ a clamping device that exerts a crushing pressure on opposite sides of the pipe and a portion of the pipe at a quarter turn from the line of thrust is without support. The result is that the casing frequently is flattened. In my invention the support is distributed around the pipe uniformly and flattening of the pipe is 10 eliminated. The arrangements in common use employ a slip approximately 6" long, and it is not feasible to substantially increase the length of the slips in the construction heretofore employed because of conflict with the other elements of the assembly. The slip of my invention in a holder to handle the same size casing, would be 14" long. The 15 advantage of this is not only to secure a better grip on the pipe and eliminate flattening of the pipe, but the greater area of contact of my slips with the pipe reduces unit pressure on the pipe and also prevents slippage 20 of the pipe. It frequently happens in the devices now employed for inserting a casing into a deep well, that the slips contact with the pipe at points only, or have a line contact; the slips do not hold the pipes securely 25 and in deep wells, after the load on the holder has become great by reason of the pipe inserted in the well, the pipe slips and drops. This frequently results in a damaged casing or bad fishing jobs, from which even the wells are sometimes lost, and in any event entails great expense on the owner.

1^a is the liner of a socket 13 in the base. The liner may be held by a key 6 and a screw 7 or by any other suitable means. 2^a and 2^b are caps on the ends of the link 2, and may be held on the link by a pin or in any suitable manner. Pins 8 are provided which pass through aligning bores in the base, wear caps, and links as shown at 14 to provide the lower 30 pivotal connection, and pass through aligning bores in the jaws, wear caps and links as shown at 15 to provide the upper pivotal connection of the links. 3^a is a liner in the jaw 3, held in place in the same manner as the liner in the base. For manual manipulation of the jaws when desired an arrangement of links A, crank shaft B, and a lever C may be employed, and such an arrangement is illustrated on the drawings, but as 35 this manual operating means has long been

known and used in this and other arts, it is shown herein only for purposes of illustration. The usual slip connections 12 are provided between the jaws to assume their movement in unison.

The base member may be of any desired shape, but preferably as shown in the drawing to eliminate excess weight. The base is provided with a circular opening through which the pipe passes. It is essential in a 70 casing holder employed at the derrick floor, that means be provided whereby the holder may be removed, in case of emergency, from around the casing suspended in the well. As the casing stands suspended from an elevator a one piece base holder cannot be removed. The very great loads imposed on these holders have a tendency to spread any assembled base or frame work, and conventional holders frequently fail at critical moments. 75

To overcome this weakness of existing construction, my invention is constructed of two segments; one of the segments D carrying three of the jaw supporting links in three 80 sockets 13 and the other segment E carrying one jaw supporting link in a single socket 13. One of the abutting faces of the larger segment D is shown in Fig. 5 with recess 1^b therein, and the smaller of the two segments 90 (Fig. 4) is formed with projecting portion 1^c, that closely fits the recess. The other abutting faces of the segments are bolted together as at F. The projection 1^c is so disposed in the recess 1^b that the axis of the projection is at right angles to the line of thrust 95 on the bearing of the smaller segment E of the base. 100

It is to be observed that the thrusts due to the load on the holding mechanism are all 105 passed on radial lines through the links to the bearing on the base. One particular advantage of this arrangement is that the slip segments adjust themselves much more efficiently to the outside of the pipe than is possible in devices known to the trade where the supports are placed at a tangent to the circle of the pipe. An arrangement of supports at a tangent tends to twist the slips and thereby bring about a line contact with the pipe 110 instead of an area in contact. 115

It will, of course, be understood that the 120 tendency of the jaws is to fall toward each other about the pivotal connection of the link with the base so that they will therefore instantly grip a pipe passing downwardly through the holder. When the pipe in the holder is lifted by means of the elevator, the friction contact of the jaws on the pipe opens the holder as the pipe is lifted. The jaws may be placed and held open by manual means, or by the application of steam, air, or other pressure applied through well known 125 operating means to the lever C. The jaws 130

form a segmental pipe gripping bowl or ring 10 as shown in Fig. 2.

I claim:

1. In a well casing holder, a base, a segmental pipe clamping bowl, the segments of said bowl comprising jaws, a link connecting each jaw with said base, a plurality of segmental slips mounted in each jaw, a bracket mounted on each end of said jaw and extending inwardly thereof beyond the jaw and provided with vertically disposed circular apertures therein, said segmental slips each having a projection from each end thereof of a smaller diameter than said apertures and adapted to be inserted therein to securely hold the slips loosely within the jaws.

2. A well casing holder having a plurality of jaws, each jaw having a plurality of slips, each slip being pivotally mounted to the jaws to have independent rotary movement of accommodation to the surface of the well casing, and means for supporting and operating the jaws, substantially as described.

3. In a well casing holder, a substantially annular base comprising two segments adapted when connected together to completely surround the well casing and when disconnected to permit lateral removal of the base from the casing, said base having a pair of diametrically opposite jaw link supporting sockets and said base having a second pair of diametrically opposite jaw link supporting sockets, the diametrical lines of said pairs being at right angles to each other, one of said segments being the larger and having three of said sockets and the other segment having one socket, the smaller segment bearing one socket having a projection extending at right angles to the said diametrical line of said socket, and the larger segment having a bore to receive said projection, said segments being bolted together.

4. In a well casing holder, a substantially annular base comprising a large segment and a small segment removably secured to and adapted to be completely disconnected from said large segment, said small segment when completely removed leaving an opening in the annular base large enough to permit lateral entry or removal of a drill pipe, said small segment at one end having a lateral interlocking projection, and said large segment at its corresponding end having a bore to receive said projection, said segments abutting at their opposite ends and being bored in alignment substantially tangentially relative to the base, and at right angles to the axial line of said projection and bore, and a clamping bolt extending through said aligned bores to clamp the segments together in interlocking relation.

5. Apparatus according to claim 4, in which said base has four jaw link supporting sockets equally spaced about its annular surface, said large segment having three of said

sockets and said small segment having one of said sockets, the axial line of said interlocking projection and bore being at right angles to the direction of jaw link thrust to be exerted against the socket in said small segment.

6. In a well casing holder, a base, a jaw, a link pivotally connected at its ends to said base and jaw for rocking movement in a plane vertical with respect to said base, and pipe slip segments having substantially vertical pivots, said slip segments being self-adjustable in said jaw about said substantially vertical pivots.

7. In a well casing holder, a base, a jaw, a link pivotally connected at its ends to said base and jaw, the axes of said pivots being horizontal, and pipe slip segments having substantially vertical pivots, said segments being self-adjustable in said jaws about said substantially vertically disposed pivots, there being clearance about said vertical pivots to permit horizontal shifting movement of said slips with respect to said jaw.

8. In a well casing holder, jaws to grasp the casing, links connecting the jaws and holder, said holder including a base in sections, one section being separable from the other by a movement along a line substantially parallel to a tangent of the central opening in the base, pin and socket interlocking means for said sections formed integral with said sections which will permit said separating movement but will resist thrust substantially radial to said central opening, the axis of the assembled pin and socket being horizontal, and means extending horizontally through the sections and at right angles to the axis of the pin and socket and connecting the sections together to resist withdrawal of the pin from the socket, said first mentioned section having a bearing for a link adjacent the interlocking means, the axial line of the pin and socket being at right angles to the line of thrust of said link, substantially as described.

9. In a well casing holder, a base in sections, jaws to grasp the casing, links connecting the jaws and base, one section of the base being separable from the other by a movement substantially parallel to a tangent of the central opening, interlocking means for said sections formed integral with said sections which will hold them together against radial thrusts, but will permit said separating movement, a bolt for holding the sections together, said bolt extending horizontally through the sections substantially at right angles to the line of said separation movement, said first mentioned section having a bearing for a link adjacent the interlocking means, the axial line of the said interlocking means being at right angles to the line of thrust of said link, substantially as described.

10. In a well casing holder, a base composed of sections separable by a relative movement horizontally, said sections defining a central aperture to receive the well casing, jaws for gripping the casing, links extending radially from the jaws outwardly, each of said separable sections of the base having the outer end of a link pivoted thereto, and means for securing the sections together, said central aperture being larger than the opening within the jaws and overhung by said jaws, the removal of one section of the base leaving an opening sufficiently large for the withdrawal of the base laterally from the casing, substantially as described.

11. In a well casing holder, jaws to grasp the casing, links extending radially of the holder and connected with the jaws, a base having bearings in which the links are pivotally mounted, said base being composed of sections; one of said sections having a face in a vertical plane substantially parallel with the vertical plane in which the link belonging to that section swings, said vertical face contacting with a face on the other section, said sections being interlocked at said contacting faces by means carried by said contacting faces and extending substantially at right angles to the plane in which the link works, said sections having other faces in contact, said latter faces being vertical and substantially at right angles to the contacting faces first mentioned and removable means for holding the sections together at the last mentioned faces, substantially as described.

12. A base for well casing holder apparatus having a central aperture for the casing, said base being composed of two sections separable from each other, one of said sections having a jaw link supporting bearing to hold a jaw link in a plane radially of said aperture, said bearing having a pivot opening, the axis of which is at right angles to the axial plane in which the link will lie, said section having a pin projecting horizontally therefrom adjacent the said bearing and parallel with the axis of the pivot, said other section having a socket to receive the pin, and a bolt for securing the sections together removably, said bolt extending horizontally and at right angles to the vertical plane in which the axis of the projecting pin lies, said section having vertical contacting faces at the pin and socket connection, and other vertical contacting faces through which the bolt passes, the latter faces being in a plane at right angles to the faces first mentioned, substantially as described.

13. In a well casing holder a base composed of severable sections defining a central opening, one section having a socket and the other section having a projection to enter said socket, said latter section being removable from the other section by a sliding

movement only which takes place only in the direction of the axis of said projection and substantially tangential to the said central opening, said removal permitting lateral separation of base and casing, and means for removably connecting the sections to resist separating movement of said latter section in the said tangential direction when the sections are coupled.

In testimony whereof, I affix my signature. 75
